UNITED STATES PATENT OFFICE.

MILLARD FILLMORE DAVIS, OF MENDENHALL, MISSISSIPPI.

AUTOMATIC CROSSING PROTECTOR.

Application filed April 30, 1927. Serial No. 187,923.

My present invention has reference to a warning signal for railway crossings.

An object of the invention is the provision of mechanical means operated by a train approaching a crossing for automatically throwing signals at the crossing to signaling position so that traffic will have ample warning that a train is approaching the crossing and wherein the signal means are also automatically returned to initial or non-signaling position by the train mechanism after the train has passed the crossing.

A still further object is the provision of a warning or danger signal for railway crossings which shall include both a signal arm or semaphore and a normally housed lamp, both of said signals being simultaneously and automatically swung to signaling position, partly across a railway crossing through the medium of a striker element supported at the front of an engine approaching the crossing from either direction, the said striker engaging contacts associated with the signal mechanism for first throwing the signals to signaling positions and thereafter returning the said signals to non-signaling positions after the train has passed the crossing, the striker element being so connected to the engine as to permit of the said engine backing over the crossing without affecting the signaling mechanism.

To the attainment of the above broadly stated objects and many others which will present themselves as the nature of the invention is better understood, the improvement further consists in certain other novel features of construction, combination and operative association of parts, one satisfactory embodiment of which is disclosed by the accompanying drawings.

In the drawings:

Figure 1 is a plan view illustrating the application of my improvement.

Figure 2 is a sectional view approximately on the line 2-2 of Figure 1.

Figure 3 is a perspective view of the signal operating mechanism for one side of the crossing.

Figure 4 is a similar view of the mechanism employed at the second side of the crossing.

Figure 5 is a side elevation of the housing for the signal lamp, parts being in section,

and the lamp being shown projected through the housing.

Figure 6 is a plan view thereof, with parts 55 also in section.

Figure 7 is a side view of the swingable striker connected with the engine.

Figure 8 is a front view thereof.

In Figures 1 and 2 of the drawings I have shown my improvement in connection with a single track rail, but it will be obvious as the description progresses that the device may be employed with equal efficiency upon a multiple track system. Also in the drawings the 65 parts constituting the improvement are in the main exposed, but in practice the operating parts are covered as much as possible to protect the same from weather conditions.

Referring now to the drawings in detail, 70 the numeral 1 designates a track, 2 the ties upon which the rails are spiked and 3 the crossing.

In the showing of the drawings on or between two of the ties 2, outward with respect 75 to the track there are hingedly supported the offset ends or feet portions of a substantially U-shaped contact member 4. The U-shaped member 4 has pivotally connected to the center thereof a link 5, and the link in turn is 80 pivoted to a rod 6 which is directed toward the crossing 3. The rod 6 is arranged to slide through suitable bearings 7 fixed on the ties 2, and the second or free end of the rod is connected to a link 8 which is pivotally sup- 85 ported upon one of the cranked portions 9 of a shaft 10. The links 5 and 8, it will be noted are directed at opposite angles toward each other and the crank shaft 10 is journaled in suitable bearings and is arranged transverse- 90 ly beneath the rails 1 at one side of the crossing 3. The second crank portion of the shaft 10 is indicated for distinction by the numeral 11 and this crank portion is disposed at the second side of the track in somewhat close 95 proximity to the second rail of the track. The shaft 10, at a suitable distance outward of its crank portion 9 is bent angularly to provide the same with an upwardly directed arm 12 and this arm carries at its outer end a signal 13. The arm 12 has pivoted thereto a link 14, the free end of the link being pivoted to an outstanding lug 15 on one edge 100 of a slide 16. The slide is in the nature of a

flat plate and supports upon its upper face adjacent to one end thereof a signal or warning lamp 17. The slide is movable through the bottom of a housing 18, and one side of the housing has an elongated slot 19 there-through for the reception of the lug 15. The housing 19 is suitably supported upon uprights 20 at one side of the crossing 3, as clearly disclosed by Figures 1 and 2 of the drawings.

The arm 12 of the crank shaft 10 has an outwardly directed portion 21 to which is pivoted a link 22. The link 22 is directed downwardly through a hollow member preferably in the nature of a pipe 23 embedded transversely in the crossing, as clearly disclosed by Figures 1 and 2 of the drawings. The link 22 is pivotally connected to a rod 24 in the hollow member 23, the said rod being guided through suitable bearings 25. The second end of the rod is connected to a lateral extension on a depending arm 26 projecting from the base of a substantially U-shaped contact member 27. The base of the contact member is supported in suitable bearings 28, as clearly disclosed in Figures 1 and 2 of the drawings. The contact member 27 has pivoted thereto a link 29, which in turn is pivoted to a rod 30, similar to the rod 6. The rod 30 is slidable through suitable bearings 31 and is, of course, directed along the track at the opposite side of the crossing than that on which the rod 6 is arranged. The rod 30 is pivotally connected to a link 33 which in turn is pivoted to one of the crank portions 34 of a shaft 35, the said shaft being journaled in suitable bearings 36 in one of the ties 2. The second crank portion of the shaft 35 is for distinction indicated by the numeral 37 and is arranged in a line with the crank portion 11 of the shaft 10 and is disposed at an angle or inclination with respect to the crank portion 34 on the shaft 35.

On the support or the cowcatcher at the front of the locomotive 38 there is fixed a bracket 39. The bracket has outstanding spaced lugs or fingers 40 between which there is pivoted, as at 41, a depending finger 42. The finger is swingable outwardly from the bracket 39, but is held from such swinging in an opposite direction by contact with the bracket.

The parts are in non-signaling position when in the full line positions as disclosed by Figure 1 and 2 of the drawings. It is, of course, to be understood that the contact 4, and the contact provided by the crank portion 37 of the shaft 35 are arranged comparatively great distances from the crossing 3. We will suppose the locomotive approaching is in the position illustrated by dotted lines in Figure 2 of the drawings and is approaching the crossing. The striker finger 42 will engage with and swing the contact 4, moving the rod 6 longitudinally and throwing the

crank lever 10 to bring the signal 13 and the arm 12 over the crossing 3. The swinging of the arm 12 will impart a longitudinal movement to the signal lamp carrying slide 16, so that the lamp on the slide will be projected out of its housing 18 and the rays of light from the lamp will fully illuminate the crossing. When the train moves on and travels over the crossing the finger 42 will next engage with the contact 27 which, through the medium of the rod 24, will influence the crank shaft 10 to its initial position, so it will be noted that the train when approaching the crossing actuates the signaling devices and when leaving the crossing influences the said devices to non-signaling positions. Should the train approach the crossing in an opposite direction the striker finger will first engage with the contact 37 and the crank shaft 35, which imparts a longitudinal movement to the rod 24 which swings the contact 37 in the same direction as when the contact 4 is actuated and influencing the crank shaft 10 to bring the signals to signaling position. When the train passes over the crossing a striker finger will engage with the second crank and with the crank or other contact portion 11 of the crank shaft 10, swinging the said crank shaft in a reverse direction and bringing the signals to non-signaling position.

The improvement is of an extremely simple nature, and when once installed needs no attention except for the lighting and extinguishing of the signal lamps. The improvement will obviate the liability of injury to life and property on railway crossings at isolated places and while I have herein set forth a satisfactory embodiment of my improved construction as it now appears to me obviously I do not wish to be restricted to the precise details of construction as herein disclosed and, therefore, hold myself entitled to make such changes therefrom as fairly fall within the scope of what I claim.

Having described the invention, I claim:—

1. A danger signal for railway crossings, including a crank shaft journaled in bearings at a crossing, a signal arm on the shaft, a housing, a slide in the housing connected with the arm, and said slide designed to sustain a signal lamp thereon, in combination with means actuated by the train approaching the crossing for swinging the crank shaft to throw the signal arm and to slide the lamp to signaling positions and to again swing the crank shaft after passing the crossing to return the said crank shaft to initial position.

2. A danger signal for railway crossings, including crank shafts, one of which is journaled at the crossing and the other a distance away from the crossing, an angle arm on the first mentioned crank shaft carrying a signal flag, a housing, a plate slidably in the housing and connected with the arm and said plate

designed to support thereon a signal lamp which is normally arranged in the housing, links connected with the cranks of both shafts, rods connected with the links, swingably supported U-shaped members having link connections with the rods, a depending arm upon one of the U-shaped members, a

slidable rod connected to the arm, and a link connection between this rod and the end of the first mentioned crank shaft, all as and ¹⁰ for the purpose set forth.

In testimony whereof I affix my signature.

MILLARD F. DAVIS.
